UNITED STATES PATENT OFFICE.

CHARLES E. LORD, OF TARRYTOWN, NEW YORK.

DESIGN FOR A TEXTILE FABRIC.

Application filed May 31, 1923. Serial No. 6,336. Term of patent 3½ years.

To all whom it may concern:

Be it known that I, CHARLES E. LORD, a citizen of the United States, and a resident of Tarrytown, in the county of Westchester and State of New York, United States of America, have invented a new, original, and ornamental Design for Textile Fabrics, of which the following is a specification, reference being had to the accompanying drawing, forming a part thereof, wherein the essentials of the design are contrasted

by shading and accentuated by fancy weaving.

The figure represents a plan view of my design particularly adapted to a textile fabric.

What I claim and desire to secure by Letters Patent is:

An ornamental design for textile fabric substantially as shown and described.

CHAS. E. LORD.
